DESIGN FOR A HANDBAG OR SIMILAR ARTICLE

Dorris M. Scott and Evelyn Steinberg, Los Angeles, Calif., assignors to Anita-Gay Creations, Inc., Los Angeles, Calif., a corporation of California

Application May 19, 1948, Serial No. 146,456

Term of patent 14 years

(Cl. D87—3)

To all whom it may concern:

Be it known that we, Dorris M. Scott and Evelyn Steinberg, both citizens of the United States, residing at Los Angeles, in the county of Los Angeles and State of California, have invented a new, original, and ornamental Design for Handbag or Similar Article, of which the following is a specification, reference being had to the accompanying drawing, forming part thereof.

Fig. 1 is a perspective view of a handbag or similar article, showing our new design.

Figs. 2 and 3 are top plan views of the same in open and closed positions, respectively.

The opposite side of the handbag is substantially like that disclosed in Fig. 1.

We claim:

The ornamental design for a handbag or similar article, as shown and described.

DORRIS M. SCOTT.
EVELYN STEINBERG.
